UNITED STATES PATENT OFFICE.

JOHN H. LORIMER, OF PHILADELPHIA, PENNSYLVANIA.

PROPELLION OF BOATS OR VESSELS.

No. 868,199.

Specification of Letters Patent.

Patented Oct. 15, 1907.

Application filed September 26, 1906. Serial No. 336,265.

To all whom it may concern:

Be it known that I, JOHN H. LORIMER, a citizen of the United States, residing at Philadelphia, Philadelphia county, Pennsylvania, have invented certain 5 new and useful Improvements in Propulsion of Boats or Vessels, of which the following is a full, clear, and exact description.

My invention relates to improvements in the propulsion of vessels.

10 The object of the invention is to provide a simple and reliable system and apparatus which may be readily controlled and which will operate efficiently for the propulsion of vessels by means of fluid streams. I am aware that it has previously been proposed to propel 15 vessels by means of a number of intermittently operating jets, by powerful isolated jets, and by a plurality of jets of large cross sectional area.

It is my object to avoid the difficulties of installation, operation and control of all such systems, and to provide 20 a system having greater efficiency and operating with less shock or disturbance to the vessel.

These objects are attained by the employment of means in the system hereinafter described.

Theoretically, the reactive or propulsive force of any 25 jet should be determined by its own momentum. Practically this is not so, partly on account of the effect of the jets upon the fluid of flotation. I have found that the only part of the jet which produces a useful and available reaction is at the edge of the discharge orifices. Edge velocity is therefore more important than 30 mass, since in any case the reactive momentum is dissipated almost instantly after the stream leaves the orifice. I therefore reduce the cross sectional area of the orifice so that the fluid ejected is simply a thin 35 stream having a maximum edge surface, and I eject a large number of these streams at very high velocities from along the bottom of the vessel so as to preserve the full effect of the edge velocity of the streams without disturbing the fluid of flotation affected by the adjacent streams.

40 Such a system is carried out in its preferred form by means of conduits forming internal or external integral parts of the body of the vessel and capable of resisting great internal as well as external pressures and strains incident to the operation of the 45 vessel, each conduit having a number of very narrow slot openings or outlets leading into the fluid of flotation in a direction opposite to the desired direction of movement of the vessel. Fluid is supplied to these conduits under great pressure and ejected from the 50 outlets continuously at high velocity, suitable pumps or other pressure producing mechanism being provided for maintaining the pressure in accumulating or distributing reservoirs. Control of the fluid pressure and discharge may be conveniently effected from the bridge 55 or pilot house of the vessel by means of electrically, mechanically or pneumatically operated valves or similar

devices. The forward as well as the backward and steering movements of the vessel may be produced by means of my invention. For a vessel of say 700 feet length and 75 feet beam, the proportion and arrangement of the conduits and discharge outlets or orifices may be stated as follows: The conduits may be three feet wide and spaced apart from each other one foot, and extend longitudinally nearly the entire length of the vessel. Each conduit may be provided with orifices or outlets 60 extending across the conduit and of a length substantially the same as the width of the conduit, say three feet, and should be very narrow, say one-sixtyfourth of an inch in width. The slots in each conduit should then be spaced apart from each other a distance say of 65 one foot. The fluid ejected from each orifice and from each conduit will with such a construction not interfere in any manner with the fluid ejected from the next adjacent orifice in the same conduit or adjacent conduits and will not disturb the fluid of flotation into 70 which the adjacent orifices discharge.

On account of the relative proportions of the conduits and outlets it is necessary to illustrate the invention diagrammatically in the accompanying two sheets of drawings.

Figure 1 is a view of the bottom of a vessel embodying the improvements of my invention, showing the arrangement of six series of discharging outlets for forward propulsion and four series for backward propulsion. Fig. 2 is a plan view showing conduits with outlets for steering. Fig. 3 is a vertical cross section showing the reservoirs and outlets. Fig. 4 is a fragmentary view showing the outlets from two adjacent conduits. Fig. 5 is a fragmentary longitudinal sectional view of one of the conduits.

The vessel whose hull or body is indicated at 1 is provided with longitudinal conduits built in and forming permanent parts of the framework, preferably along the bottom for forward and rearward propulsion, and along the sides for steering purposes. The forward propulsion outlets are indicated by the series 2—2, the rearward propulsion outlets by the series 3—3. The steering propulsion conduits 4—4 are for port turning, and conduits 5—5 for starboard turning movements.

On Sheet 2 of the drawings, in Fig. 5, is illustrated a 100 fragment of one of the conduits or troughs indicated at 6 and having a plurality of orifices or outlets 7—7 inclined in the direction of the length of the trough or conduit. It is preferred to provide a staggered arrangement of orifices of the adjacent conduits, particularly 105 where the adjacent conduits are used for propulsion in the same direction, for instance as shown in Fig. 4. In this way it is possible to provide the conduits closer together without interference in the fluid of flotation.

The fluid of propulsion is supplied to the conduits at 110 high pressure in order that the discharge may be effected at high velocity. The required pressure may be ob-

tained by suitable pumps, engines or other apparatus, of any suitable type. It is preferred to store the propelling fluid in a reservoir in which the proper pressure may be maintained. Such a reservoir is indicated at 8 5 in Fig. 3.

9 indicates any suitable means for storing the fluid at high pressure within the reservoir 8.

In order to make the operation of the system and apparatus as uniform as possible, it is in some cases desirable, for instance where water is the propelling fluid, to provide in addition to the fluid compressing or pumping apparatus a suitable means for furnishing additional elastic pressure, such as air compressors or air pumps, as indicated at 10. The flow of the fluid to the orificed 15 conduits may be controlled in any suitable manner. In vessels of large size in some cases it may be desirable to employ additional reservoirs in auxiliary or intermediate capacity, so that a supply of operating fluid may be at hand in the immediate vicinity of those portions 20 of the conduit through which it is desired to eject the propelling fluid.

I have indicated intermediate reservoirs in Fig. 3, where 11 is a reservoir for supplying fluid to the forward operating conduits, 12 is a reservoir for supplying 25 fluid to the rearward or backward propelling conduits, 13 is a reservoir supplying fluid to one of the steering conduits, and 14 is a reservoir for supplying fluid to another steering conduit. These intermediate reservoirs may be in continuous communication with the main 30 reservoir and the control of the ejection effected between the immediate reservoirs and their respective conduits.

In Fig. 2 I have indicated at 15 an inclosure which may be considered a diagram including the main and

auxiliary reservoirs and controlling mechanism. It 35 will be noted that any arrangement of reservoirs and pressure producing mechanism may be supplied.

From the foregoing I wish it understood that I lay great emphasis upon the continuous discharge of a large number of streams of relatively small width at great 40 pressure and velocity into the fluid of flotation at such points as to produce a uniform propelling action without disturbing the fluid of flotation affected by adjacent streams.

What I claim is:

1. The means for propelling vessels by discharging under great pressure a large number of continuous fluid streams through narrow orifices arranged in series extending longitudinally of the vessel the orifices in one series being in staggered relation to the orifices in the adjacent series, each stream discharging independently and without interference with the other streams or the fluid of flotation under such other streams affected thereby, so as to utilize substantially all the velocity of the streams at the edges of the orifices. 45

2. In a vessel, the combination of a plurality of longitudinally arranged conduits built into the body of the vessel and supplied with outlet passages spaced apart along the length of the vessel and of relatively very narrow width and opening in a direction opposite to the direction of desired propulsion, the outlet passages in one conduit being in staggered relation to the outlet passages in the adjacent conduits, and suitable pumping and supply mechanism for maintaining a high continuous pressure in the discharge conduits for ejecting the propelling fluid continuously in thin streams at a high velocity and utilizing substantially all the velocity of the streams at the edges of the outlet passages. 50 60 65

JOHN H. LORIMER.
